UNITED STATES PATENT OFFICE

STANLEY G. COOK, OF AUBURN, NEBRASKA

HEATING STOVE

Application filed April 23, 1929. Serial No. 357,553.

The present invention relates to a heating stove and has for its prime object to provide a stove of this nature for burning oil and enables a room or the like to be heated and maintained at a proper temperature in a very effective manner.

Another very important object of the invention resides in the provision of a heater of this nature which is exceedingly simple in its construction, inexpensive to manufacture, strong and durable, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

20 In the drawing:

Figure 1 is a side elevation of the heater embodying the features of my invention,

Figure 2 is an end elevation thereof,

25 Figure 3 is a vertical longitudinal section therethrough,

Figure 4 is a detail vertical transverse section taken substantially on the line 4—4 of Figure 3,

Figure 5 is a sectional view taken substantially on the line 5—5 of Figure 3,

Figure 6 is a horizontal section taken substantially on the line 6—6 of Figure 1, and

Figure 7 is a perspective view of one pair of end doors.

30 Referring to the drawing in detail it will be seen that a hood is constructed of side walls 5, end walls 6, and top wall 7 and portions of which are inclined downwardly and outwardly as is indicated at 8. These walls 5,

40 6 and 7 are formed of sheet metal and suitably secured together. Asbestos lining 10 is provided for the side walls 5, asbestos lining 11 is provided for the end walls 6, and a sheet metal lining 12 is provided for the top wall 7

45 and adjacent the clamping end portions 8

thereof is spaced therefrom so that relatively thick asbestos 14 may be disposed therein. A casting 15 is mounted on the center of the top 7 to receive a smoke pipe 16 which extends therethrough and through a registering opening in the top and terminates at its bottom end a distance above the lower edges of the side and end walls and interiorly of the hood is braced as is indicated at 17.

50 A damper 18 is rockably mounted in the stack or pipe 16 above the hood. The end walls 6 are provided with transverse elongated openings 19. Oil tanks 20 are mounted on the portions 8 of the top 7 by means of cradle brackets 21 and pipes 22 lead downwardly from the tanks to burners 23 controlled by valve means 24 incorporated in the piping 22.

55 End fire boxes are formed by inwardly extending horizontal plates 25 connected to the end walls adjacent the lower edges of the opening 19 and at their inner ends merging into inwardly and upwardly inclined extensions 26 which in turn merge into vertical extensions 27 terminating a distance below the 60 top portions 8.

65 The plates 25 and their extensions 26 and 27 are provided at their side edges with flanges 28 secured to the sides 5. A plurality of arrows 31 indicate the passage of products of combustion showing circuitous paths so that the maximum amount of heat may be obtained therefrom. The burners, of course, are located on the plates 25.

70 A pair of doors 36 are associated with each opening 19 being slidably mounted by suitable means 37 and the inner edges thereof are notched as at 38 to accommodate the piping 22 and knobs 39 are provided on the doors so that they may be opened and closed.

75 These doors, of course, are opened and closed to regulate the draft desired or needed.

80 From the above detailed description, it will be seen that I have devised an exceedingly simple stove which may be heated up very 85

quickly and may be maintained at the proper temperature very economically. Furthermore it will be noted that the structure is simple, yet may be constructed strong and durable.

5 The present embodiment of the invention has been disclosed in considerable detail merely for the purposes of exemplification since in actual practice it attains the features of 10 advantage enumerated as desirable in the statement of the invention and the above description.

It will be apparent that changes in the details of construction, and in the combination 15 and arrangement of parts may be resorted to without departing from the spirit or scope of the invention as hereinafter claimed or sacrificing any of its advantages.

Having thus described my invention, what 20 I claim as new is:

1. A stove of the class described comprising a hood including a pair of side walls, a pair of end walls, and a top the end portions of which incline downwardly and outwardly, 25 said end walls being provided with openings, plates extending inwardly from the end walls adjacent the lower edges of the openings and having upwardly directed extension terminating in spaced relation to the top wall, 30 burners located on said plates, oil tanks located on the inclined portions of the top, and piping connecting the tanks with the burner, valve means incorporated in said piping, and a smoke stack extending through the center 35 of the top and disposed vertically and terminating at its lower end a distance from the bottom edge of the side.

2. A stove of the class described comprising a hood including a pair of side walls, a pair of end walls, and a top the end portions of which incline downwardly and outwardly, 40 said end walls being provided with openings, plates extending inwardly from the end walls adjacent the lower edges of the openings and having upwardly directed extension terminating in spaced relation to the top wall, 45 burners located on said plates, oil tanks located on the inclined portions of the top, and piping connecting the tanks with the burner, valve means incorporated in said piping, a smoke stack extending through the center of the top and disposed vertically and terminating at its lower end a distance from the bottom edge of the side, and doors associated 50 with the openings of the end walls.

3. A stove of the class described comprising a hood including a pair of side walls, a pair of end walls, and a top the end portions 55 of which incline downwardly and outwardly, said end walls being provided with openings, plates extending inwardly from the end walls adjacent the lower edges of the openings, burners located on said plates, oil tanks 60 located on the inclined portions of the top,

and piping connecting the tanks with the burner, valve means incorporated in said piping, a smoke stack extending through the center of the top and disposed vertically and terminating at its lower end a distance from the bottom edge of the side, and doors associated with the openings of the end walls, 70 said plates having upwardly and inwardly inclined extensions terminating in spaced relation to the inclined portions of the top.

75 In testimony whereof I affix my signature.

STANLEY G. COOK.
